UNITED STATES PATENT OFFICE.

ALEXANDER LEVIN AND JOSEPH MEDIN, OF CALUMET, MICHIGAN.

DESIGN FOR A WATCH-BRACELET.

54,936.

Specification for Design.

Patented Apr. 20, 1920.

Application filed May 24, 1919. Serial No. 299,671. Term of patent 7 years.

To all whom it may concern:

Be it known that we, ALEXANDER LEVIN and JOSEPH MEDIN, citizens of the United States of America, residing at Calumet, in the county of Houghton and State of Michigan, have invented a new, original, and ornamental Design for Watch-Bracelets, of which the following is a specification, reference being had to the accompanying drawing, forming part thereof.

We claim:—

The ornamental design for a watch bracelet, as shown.

In testimony whereof we affix our signatures.

ALEXANDER LEVIN.
JOSEPH MEDIN.
